INVENTOR

Joel Witmer.

BY

Arthur C. Brown
ATTORNEY

UNITED STATES PATENT OFFICE.

JOEL WITMER, OF KANSAS CITY, MISSOURI, ASSIGNOR TO ELIZABETH WITMER, OF KANSAS CITY, MISSOURI, DOING BUSINESS AS WITMER RECORD COMPANY.

REGISTER SYSTEM.

1,071,491.

Specification of Letters Patent. Patented Aug. 26, 1913.

Application filed February 6, 1912. Serial No. 675,796.

To all whom it may concern:

Be it known that I, JOEL WITMER, a citizen of the United States, residing at Kansas City, in the county of Jackson and State 5 of Missouri, have invented certain new and useful Improvements in Register Systems; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to a register for the keeping of accounts and records, particularly by physicians and surgeons, and has for its principal object to provide a system comprising record slips, envelops and files 20 whereby information may be tabulated and filed so that part of the information is readily accessible, and full information regarding any particular matter or case may be secured. In accomplishing this object, I 25 provide specially printed and ruled case slips and envelops adapted for disclosing the amount of the account on an exposed part of the slip when the latter is in the envelop, and a file for containing the envelop, and exposing an index portion thereof so that the particular account may be 30 readily found in the file, and by pulling the envelop from the file the amount of the patient's balance may be seen without removing the slip from the envelop. In accomplishing this object, I have provided the 35 details of structure hereinafter described and illustrated in the accompanying drawings, wherein:

40 Figure I is a perspective view of a cabinet or filing drawer constructed according to my invention, showing a number of envelops in the file. Fig. II is a front view of an envelop containing a record slip. Fig. 45 III is a detail view of a slip showing the particular ruling.

Referring more in detail to the parts, 1 designates a cabinet having a drawer 2 which is preferably divided longitudinally 50 by a rail 3. The compartment on each side of the rail is in turn divided by vertical partitions 4 to provide the narrow envelop bins 5.

While I prefer to provide a number of the 55 drawers 2, and divide same as described, I

make no special claim to this construction, as it may be divided to meet different requirements, my invention relating only to the combination of a cabinet of this kind with my particular envelops and record 60 slips.

6 designates one of the envelops, which comprises a back portion 7 and a front portion 8, the back being extended from the body to substantially twice the length thereof, in the form here illustrated.

On the free end of the back portion 7, and on what would ordinarily be the inner face of the envelop, I provide spaces for writing the name and address of a patient and the 70 disease with which he is afflicted, preferably printing the index of the information which is to be written thereon.

9 designates a record slip having spaces for writing information thereon and preferably having the information indexes printed thereon to indicate where the various items are to be written, such as the name and residence of the patient, the date, his symptoms, temperature, pulse, respiration, 80 etc.

At the bottom of the slip, and at the right-hand side thereof, are dollars and cents columns 10 and 11 for showing a balance, a new charge and the total amount of the account. This ruling may be extended, if desired, as the ruling itself is not claimed as 85 part of the invention, the feature claimed being merely the location of the ruling and its particular relation to the special envelop. 90

In using the system and devices, a physician calling on a patient may make a record of his name and address on the slip and record the charge for that visit in the 95 proper column in the right-hand lower corner of the slip. If a prescription is given it is preferably written on the back of the slip over a carbon sheet in his prescription tab, so that the carbon copy may be given to the 100 patient and the original retained as a record. When the physician returns to his office he places the record slip in one of the special envelops so that the right-hand side of the slip is at the top. The envelops are 105 so made, with reference to the slips, that when a slip is in place the only information visible above the front portion 8 is the charge at the right-hand lower corner of the slip, which slip being placed on its left- 110

hand edge in the envelop enables the charge to be shown while the mass of the information contained on the slip is hidden by the front of the envelop. The name and address 5 of the patient is then written on the front exposed face of the back portion 7 and the envelop filed in the cabinet drawer 2, which latter is constructed for the purpose of containing such envelops and is of a depth to 10 expose the name and address of the patient above the partitions 4, without exposing the charge or any other information contained on the record slips. An envelop for each of the physician's patients, having an 15 unsettled account, may be kept in the drawer so that account may be found readily in case the patient wishes to pay his bill, or if the physician wishes to look up the record of any particular case. Should the physician 20 have another call from the same patient, a new slip is made out for that particular call, and when he returns to the office he files same in the same envelop in front of the preceding slip, carrying the balance 25 of the account forward above the last charge and bringing the new balance down to the proper column.

It is apparent that with a system and device of this character a record of any particular patient, both as to physical condition 30 and account, may be simply and easily kept

so that it can be readily found when desired.

Having thus described my invention, what I claim as new therein and desire to secure 35 by Letters-Patent is:—

A register comprising an envelop having a back leaf of greater width than the front ply thereof, the edges of the back leaf and the front portion being uninterrupted and 40 parallel with each other throughout their length, the portion of the back leaf above the front ply having spaces in which to indicate the name, disease, address, and to whom the account is to be charged, and 45 an insert record slip constructed to fit in said envelop and project throughout its length above the said front ply to a point on the back leaf below the designations on the back leaf, whereby said designations are 50 always in unobstructed view, said insert having a space above the said front ply appropriately designated to show the balance due in the account without removing the insert from the envelop. 55

In testimony whereof I affix my signature in presence of two witnesses.

JOEL WITMER.
